DISPLAY RACK FOR MERCHANDISE

Robert C. Young, Jr., Dallas, Tex., assignor to Volume Shoe Corporation, Topeka, Kans.

Filed June 9, 1971, Ser. No. 151,630

Term of patent 14 years

Int. Cl. D6—04

U.S. Cl. D6—186

Fig. 1.

Fig. 2.

Fig. 3.

Fig. 4.

FIG. 1 is a side elevational view illustrating the display rack for merchandise, the other side of the fixture being identical thereto;

FIG. 2 is an end elevational view of the fixture;

FIG. 3 is a top plan view of the fixture; and

FIG. 4 is a horizontal cross-sectional view looking downwardly and taken through the center of the fixture.

I claim:

The ornamental design for a display rack for merchandise, as shown and described.
